UNITED STATES PATENT OFFICE

CHARLES F. OSGOOD, OF CLAREMONT, NEW HAMPSHIRE, ASSIGNOR TO SULLIVAN MACHINERY COMPANY, A CORPORATION OF MASSACHUSETTS

MINING APPARATUS

Application filed November 27, 1929. Serial No. 410,191.

This invention relates to mining apparatus, and more particularly to coal mining apparatus of the wheel-mounted bottom cutting type especially adapted for cutting horizontal kerfs at or near the level of the mine bottom outside the mine trackway.

An object of this invention is to provide an improved coal mining apparatus. Another object is to provide an improved coal mining apparatus of the wheel-mounted bottom cutting type adapted to operate from the mine trackway. Still another object is to provide an improved mining apparatus of the wheel-mounted bottom cutting type having a pivotally mounted cutter bar and improved means for adjusting and swinging the cutter bar whereby the bottom of the kerf cut thereby may form a continuation of the plane of the mine bottom. A further object is to provide an improved coal mining apparatus of the wheel-mounted bottom cutting type adapted to operate from the mine trackway and having improved adjustable kerf cutting mechanism whereby the kerf cutter may be positioned in an improved manner to cut a horizontal kerf at or near the level of the mine bottom outside the mine trackway. Yet another object is to provide in a mining apparatus of the aforesaid type an improved offset pivotal mounting for the kerf cutter whereby the latter may be quickly and with facility positioned with its pivot outside the mine trackway and thereafter adjusted to a position at or near the level of the mine bottom. A further object is to provide an improved adjustable cutter head for a mining apparatus. A still further object is to provide in a mining apparatus of the aforesaid type improved mechanism for tilting the kerf cutting mechanism about a transverse axis to vary the angle of the kerf cutter relative to the horizontal. Yet another object is to provide in a mining apparatus of the aforesaid type improved means for propelling the apparatus along the mine trackway at either a relatively slow cutting speed or a relatively high transport speed. These and other objects of this invention will, however, hereinafter more fully appear in the course of the follow-

ing description and as more particularly pointed out in the appended claims.

In the accompanying drawings there is shown for purposes of illustration one form which the invention may assume in practice.

In these drawings—

Fig. 1 is a side elevational view of the illustrative embodiment of the improved mining apparatus.

Fig. 2 is a plan view of the mining apparatus shown in Fig. 1.

Fig. 3 is a central, longitudinally extending, vertical sectional view taken substantially on line 3—3 of Fig. 2.

Fig. 4 is an enlarged fragmentary plan view of the apparatus shown in Figs. 1 and 2, parts being shown in section to illustrate details of construction.

Fig. 5 is a transverse horizontal sectional view taken substantially on line 5—5 of Fig. 3.

Fig. 6 is a central, longitudinally extending, vertical sectional view taken substantially on line 6—6 of Fig. 4, parts being shown in elevation.

Fig. 7 is a detail sectional view taken on line 7—7 of Fig. 4.

Fig. 8 is a detail sectional view taken on line 8—8 of Fig. 2.

Fig. 9 is a detail sectional view taken substantially on line 9—9 of Figs. 1 and 6.

Fig. 10 is a diagrammatic view illustrating the operation of the machine during arcwall cutting.

In this illustrative embodiment of the invention there is shown a coal mining apparatus of the wheel-mounted, bottom cutting type generally comprising a truck frame 1 supported by wheels 2 adapted to run along a mine trackway 3. Pivotally mounted on the truck frame 1 to rock about a transverse axis 4 is a machine frame or body 5 carrying at its forward end improved adjustable kerf cutting mechanism generally designated 6. Truck wheel driving mechanism generally designated 7 is provided for propelling the apparatus along the mine trackway at either a relatively high transport speed or a relatively low cutting speed. Generally designated at 8 is improved mechanism for effect-

- ing tilting movement of the machine body 5 together with the kerf cutting mechanism 6 carried thereby about the transverse axis 4 relative to the truck frame.
- 6 Supported by the tilttable machine body 5 is a motor 9 herein preferably of the reversible electric type having an armature shaft 10 (Fig. 6) extending longitudinally of the machine body. This armature shaft has secured thereto as by a key 11 a coupling member 12 which is in turn connected by interlocking teeth 13 to a coupling member 14 fixed to a shaft 15 alined with the motor armature shaft. The shaft 15 drives, as hereinafter described, the improved kerf cutting mechanism, while a spur gear 16 integral with the coupling member 12 drives the improved slow speed propulsion mechanism for the apparatus.
- 10 Now referring to the improved kerf cutting mechanism 6, it will be noted that secured as by screws 17 to the front end of the machine body is a rigid cutter carrying head 18. This cutter head is provided with vertical guideways 19 within which there are slidably mounted for vertical reciprocatory movement guides 20 rigidly secured as by screws 21 to an adjustable cutter supporting frame 22. Swivelly mounted on this adjustable frame 22 for swinging movement about a vertical axis is a laterally projecting frame or supporting arm 23 which herein forms an offset pivotal mounting for the kerf cutter. Pivottally mounted on the outer end of this arm 23 is an elongated plane cutter bar 24 carrying on its margin an endless cutter bit carrying cutter chain 25. The improved offset pivotal mounting for the cutter bar 24 includes a circular frame 26 supporting the cutter bar and having a radial flange 27 guided within an annular guideway formed by the lower surface of the supporting arm 23 and an annular thrust plate 28 secured as by screws 29 to the bottom of the arm 23.
- 15 This thrust plate has an inwardly projecting flange 30 underlying the flange 27, as clearly shown in Fig. 3. Formed integral with the frame 26 supporting the cutter bar is a hub portion 31 mounted for rotative movement on a bearing sleeve 32 in turn supported by an annular hub 33 depending from the arm 23 at the outer end thereof. The means for locking the cutter bar 24 in its different angular positions relative to the arm 23 herein includes a releasable locking pin 34 (Figs. 2 and 3) receivable in any one of a series of apertures 35 formed in a radial flange 36 integral with the arm 23. When the cutter bar is suitably positioned relative to the supporting arm, the locking pin 34 is inserted in the proper aperture and into engagement with a registering aperture or notch 37 formed in the frame 26 supporting the cutter bar. It will thus be seen that the cutter bar 24
- 65 may be swung relative to the supporting arm

23 and rigidly locked thereto in its different angular positions by means of the locking pin 34.

The improved mechanism for driving the cutter chain 25, for swinging the cutter supporting arm 23 about its pivotal axis, and for adjusting the cutter bar into different parallel planes, will now be described. As shown in Fig. 3 secured as by a key 40 to the forward end of the shaft 15 is a bevel pinion 41 having its hub portion journaled within an anti-friction bearing 42 carried by the cutter head frame. The bevel pinion 41 meshes with a large bevel gear 43 enclosed within the cutter head frame and rigidly secured as by screws 44 to a nut element 45. Coaxial with this nut element is a splined sleeve 46 which at its upper end is keyed or otherwise secured to a sleeve member 46. This sleeve member is connectible alternatively by a sliding clutch device 47 to a stationary member 48 rigidly secured to the cutter head frame 18 or to the nut member 45. If desired, the member 48 may be connected to the cutter head frame by a yieldable clutch device or slip friction as described in a copending application to one C. G. Boudette, Serial No. 694,222, filed Feb. 21, 1924, now matured into Patent No. 1,819,697, patented Aug. 18, 1931. Suitable clutch operating mechanism including a pivoted shipper yoke 49 engaging a shiftable clutch element 50 of the clutch device and a lever 51 is provided for actuating clutch device 47 (see Figs. 1 and 2). Threadedly engaging the nut 45 is a vertical screw shaft 52 having longitudinal splineways 53 therein cooperating with splines 54 upon the sleeve member 46. This screw shaft 52 has a collar 55 thereon engaging a suitable combined bearing and supporting means 56 for the adjustable cutter supporting frame 22 and the mechanism supported thereby so that the screw shaft 52 is adapted to effect vertical adjustment of the frame 22 relative to the guideways 19 on the cutter head to position the cutter bar into different parallel horizontal planes. It will thus be seen that when the clutch device 47 is moved into a position to connect the sleeve 46 to the stationary member 48, the screw shaft 52, due to its splined engagement with the sleeve 46, is held against rotation and that upon rotation of the nut member 45 the screw shaft 52 is moved axially to effect vertical adjustment of the cutter supporting frame 22. It will also be noted that when the clutch device 47 is shifted into its opposite position connecting the sleeve 46 to the bevel gear 43, the sleeve 46 and screw shaft 52 may be rotated together in fixed angular relation without axial adjustment of the shaft, and at that time the screw shaft acts as a transmission shaft for effecting drive of the cutter chain 25 and the bar swinging mechanism. The driving connections between the shaft 52 and the cutter chain include a clutch member 57

fixed as by a key 58 to the shaft 52 and connectible by a shiftable clutch member 59, having any suitable operating means, to a clutch member 60, in turn fixed as by a key 61 to the hub of a chain drive sprocket 62. This sprocket is rotatably supported on the lower end of the screw shaft 52 and is held in position by means of a suitable screw and washer connection 63. The drive sprocket 62 drives

10 through an endless chain connection 64 enclosed within the supporting arm 23 a chain sprocket 65 suitably fixed to a vertical shaft 66 carried at the outer end of the arm 22, as shown in Fig. 3. This shaft is journaled in 15 anti-friction bearings 67 carried by the supporting arm 23 and has suitably fixed thereto at its lower end a drive sprocket 68 which engages and drives the endless cutter chain 25.

The improved mechanism for effecting 20 pivotal movement of the cutter supporting arm 23 about its pivotal axis includes a spur gear 70 fixed as by a key 71 to the clutch member 57 which is in turn secured to the shaft 52. As shown in Fig. 5, the spur gear 70 25 meshes with spur gears 72 and 73. Referring more particularly to the mechanism for effecting swinging movement of the cutter supporting arm 23 at a relatively slow cutting speed, it will be observed that rotatable 30 with the spur gear 72 is a worm 74 meshing with a slow speed worm wheel 75. This worm wheel is connectible by a manually controllable friction clutch 76 of a usual design to a transverse shaft 77 suitably journaled within the adjustable frame 22. This 35 transverse shaft has suitably fixed thereto intermediate its ends a worm 78 meshing with a worm wheel 79 suitably journaled within the frame 22. This worm wheel is 40 secured as by a key, as shown in Fig. 3, to a vertical shaft 80 having formed integral therewith a spur pinion 81. This spur pinion meshes with the teeth of an internal gear 82 rigidly secured as by screws 83 to the cutter supporting arm 23. Secured as by 45 screws 84 to the adjustable frame 22 is an annular member or thrust washer 85 which together with an annular shoulder 86 upon the frame 22 provides a circular guideway 50 for the large internal gear 82 to which the cutter supporting arm 23 is secured. The fast speed swinging means for the cutter supporting arm 23 includes a worm 87 rotatable with the spur gear 73 and meshing 55 with a fast speed worm wheel 88 having its teeth oppositely inclined from and of greater inclination than the teeth of the worm wheel 75. This worm wheel 88 is operative upon application of a manually controllable friction clutch 89, similar to the clutch 76, to 60 drive the shaft 77 at a relatively fast speed in a direction opposite from the slow speed drive. It will thus be seen that upon application of one or the other of the friction 65 clutches 76 and 89, the cutter bar supporting

arm 23 together with the cutter bar supported thereby may be swung at a relatively high positioning speed in one direction and at a relatively slow cutting speed in the opposite direction. As the specific driving mechanism for the cutter chain and the specific mechanisms for adjusting the cutter bar into different parallel planes and for swinging the cutter bar are clearly described in a copending application to one Morris P. Holmes, Serial No. 694,139, filed Feb. 20, 1924, now matured into Patent No. 1,819,778, patented Aug. 18, 1931, and do not per se enter into this invention, further detailed description of their structure is thought unnecessary.

The mechanism 8 for swinging the tiltable machine body 5 about its transverse axis relative to the truck frame is also clearly described in the above mentioned Holmes application and herein includes a transverse shaft 90 rotatably mounted on the truck frame and having secured thereto a pair of similar arms 91 (see Fig. 9) which carry at their free ends rollers 92. These rollers are arranged in slots or guideways 93 formed in members 94 which are secured to the bottom of the machine body. It will be noted that when the machine body is in its horizontal position the arms 91 are not vertical but inclined so that on rotative movement of the shaft 90 the resultant swinging of the arms 91 may cause tilting movement of the machine body relative to the truck frame in either direction about the transverse axis 4. For the purpose of rocking the shaft 90 and holding it in its different angular positions an arm 95 is suitably rigidly secured to one end of the shaft 90 and with this arm there cooperates arm swinging means comprising a screw 96 pivotally connected to the arm at 97. This screw is supported in suitable horizontal guides 98 and is adapted to be moved longitudinally upon rotation of a nut 99 which threadedly engages the screw and is rotatable by a hand operated ratchet and pawl mechanism 100. It is to be observed that, depending upon the direction in which the nut 99 is turned, the arm 95 and so the arms 91 will be swung in opposite directions and the machine body either tilted toward or from its horizontal position.

The truck propelling mechanism 7 includes a spur gear 101 meshing with the spur gear 16 secured to the coupling member 12 (see Figs. 4 and 6) and the gear 101 is rigidly fixed as by a key 102 to a horizontal, longitudinally extending shaft 103. This shaft 103 is suitably journaled within the machine body and has fixed thereto at its forward end a bevel pinion 104 meshing with reverse bevels 105, 106. These reverse bevels are alternatively connectible by friction clutches 107 and 108 of a usual design to a transverse shaft 109 suitably journaled within the machine body. Secured to this shaft is a worm

110 meshing with a worm wheel 111 (see also Fig. 7) suitably secured as by a key to a longitudinally extending horizontal shaft 112 suitably journaled in the machine body. This shaft 112 has suitably fixed thereto a worm 113 meshing with a worm wheel 114 suitably journaled on a transverse shaft 115 in turn journaled within the machine body. This worm wheel 114 is at will connectible to or releasable from the shaft 115 by a shiftable clutch device 116 having suitable operating mechanism including a handle 117 (see Figs. 1 and 2). Secured to the outer end of the shaft 115 is a chain sprocket 118 connectible by an endless chain connection 119 to a chain sprocket 120 suitably fixed in the rear truck axle. The front and rear truck axles are connected in driving relation by means of a chain and sprocket connection 121. As best shown by dotted lines in Fig. 1, the chain 119 passes around a sprocket 122 which is adjustable in positions to vary the tension of the chain as the machine body is tilted relative to the truck frame. This sprocket 122 is carried, as shown in Fig. 9, by an arm 123 suitably fixed to the shaft 90 and it will be evident that if this shaft is rotated to effect tilting movement of the machine body relative to the truck frame, the position of the sprocket 122 is changed, thereby varying the tension of the drive chain 119 during such tilting movement. The chain 119 also passes around a sprocket 124 which, when connected in driving relation with the motor as hereinafter described, constitutes a fast speed driving element for the truck wheels. From the foregoing description it is evident that when one or the other of the friction clutches 107, 108 is applied the truck wheels may be driven from the motor 9 through spur gearing 16, 101, bevel gear 104, one or the other of the reverse bevels 105, 106, worm gearing 110, 111, 113 and 114, and the chain and sprocket connections 118, 119 and 120 (it being understood that the clutch device 116 is positioned to connect the worm wheel 114 to the shaft 115 at that time) at a relatively slow speed either forwardly or rearwardly along the mine trackway.

The mechanism for effecting propulsion of the apparatus along the mine trackway at a relatively high transport speed includes a spur pinion 125 (see Fig. 8) suitably fixed to the rear end of the armature shaft 10. This spur pinion meshes with a spur gear 126 which drives a worm 127 meshing with a worm wheel 128. This worm wheel is connectible by a manually operable friction clutch device 129 to a transverse shaft 130 to which the chain sprocket 124 is secured. It will thus be seen that when the clutches 107, 108 and 116 are released and the clutch device 129 is applied, the truck wheels may be driven from the motor through the spur gearing

125, 126, worm gearing 127, 128, transverse shaft 130 and the chain and sprocket connection 124, 119, 120, to effect propulsion of the mining apparatus forwardly along the mine trackway at a relatively high speed. Upon reversal of the motor 9 the truck wheels may be driven at a relatively high speed in the opposite direction.

A frictional braking device 131 of a usual design is provided for controlling movement of the apparatus when moving along an inclined trackway and for holding the truck wheels against rotation at certain times during the cutting operation, and herein includes a brake drum 132 secured to the rear axle of the truck and a cooperating brake band 133. This brake band is controlled by means of a suitable lever mechanism 134 connected through a pull rod 135 to a suitable operating handle 136 (see Fig. 1).

The general mode of operation of the improved mining apparatus will now be described. The apparatus is propelled about the mine at a relatively high transport speed under the control of the friction clutch device 129. When the working face is reached and it is desired to insert a horizontal cut at the base of the mine wall at or near the level of the mine bottom, the operator applies the fast speed controlling friction clutch 89, thereby effecting horizontal swinging movement of the cutter bar supporting arm laterally from its central position shown in Fig. 2. As the cutter bar supporting arm 23 is swung laterally the locking pin 34 is released, unlocking the cutter bar from the supporting arm 23 and when the outer end of the cutter bar engages the right hand rib, swinging movement of the supporting arm 23 is continued until the bar pivot is positioned outside the mine trackway, the parts assuming the position at A indicated in full lines in Fig. 10. When the parts are thus disposed, the cutter bar 24 is again rigidly locked to the supporting arm 23 by the locking pin 34. The clutch device 47 is then shifted upwardly into a position to connect the sleeve 46 to the stationary member 48 and as a result the sleeve 46 is held against rotation. As the nut 45 is rotated relative to the non-rotatable screw shaft 52 the latter is fed axially downwardly, thereby lowering the adjustable frame 22 relative to the guideways 19. When the cutter bar 24 is positioned in a plane at or near the level of the mine bottom, the clutch device 47 is shifted downwardly to release the sleeve 46 from the stationary member 48 and to connect the sleeve 46 to the nut member 45. The parts 45, 46, and 52 then rotate together at the same angular rate without any axial adjustment of the screw shaft 52. The operator then shifts the clutch member 59 to a position to connect the chain sprocket 62 to the clutch member 57 keyed to the lower end of the screw shaft 52, thereby

effecting circulation of the cutter chain 25 about the margin of the cutter bar through the chain and sprocket connection 62, 64, 65 and the cutter chain drive sprocket 68. The operator then applies the slow speed truck drive controlling clutch 108 and upon connection of the clutch 116 the apparatus is propelled bodily forwardly along the mine trackway at a cutting speed, thereby sumping the cutter bar 24 beneath the mine wall until it assumes the dotted line position indicated at B in Fig. 10. The frictional braking device 131, 132 is then set and the truck wheels are held against rotation. The locking pin 34 is then released and the slow speed clutch 76 applied, thereby effecting swinging movement of the cutter supporting arm 23 laterally from right to left until the arm and cutter bar assume an alined position, the cutter bar then again being rigidly locked to the supporting arm 23 by the locking pin 34. The cutter supporting arm 23 and the cutter bar are then swung simultaneously about the pivotal axis of the supporting arm from right to left across the coal face thereby effecting a transverse cut. When the outer end of the cutter bar reaches the left hand rib, the locking pin 34 is again released and upon continued swinging movement of the supporting arm 23 the parts assume the position indicated at C in Fig. 10, the cutter bar thereafter being rigidly locked to the supporting arm by the locking pin. The frictional braking device 131, 132 is then released and the slow speed truck wheel controlling friction 107 is applied and upon connection of the clutch device 116 the apparatus is propelled bodily rearwardly along the mine trackway at a cutting speed, thereby withdrawing the cutter bar from the working face of the coal to the position indicated at D in Fig. 10. The cutter chain drive controlling clutch 59 is then shifted downwardly to a position to disconnect the cutter chain from the screw shaft 52. The motor 9 is then reversed and the clutch device 47 shifted to again connect the sleeve 46 to the stationary member 48 and as a result the cutter bar and cutter bar support 22 are moved upwardly to the position shown in Fig. 1 with the cutter bar a substantial distance above the top of the trackway, the clutch device 47 thereafter being released. The operator then applies the fast swing controlling clutch 89 thereby effecting swinging movement of the supporting arm 23 laterally to its central or transport position, as indicated in Fig. 2. The locking pin 34 is then released and the cutter bar swung into a central position in alinement with the supporting arm and thereafter locked by the pin 34. The apparatus is then propelled bodily rearward along the mine trackway at a fast transport speed under the control of the friction controlling clutch 129. If it is desired to make a horizontal cut above the top of the mine trackway, the cutter bar 24 is rigidly locked by the pin 34 in alinement with the supporting arm 23 and the arm and bar are maintained in alinement throughout the cutting operation. The friction clutch 89 is then applied and the supporting arm and cutter bar are swung laterally at a relatively fast bar positioning speed to a position adjacent the right hand rib, the clutch 89 thereafter being released. The slow truck drive controlling clutch 108 is then applied and the apparatus is propelled bodily forward along the mine trackway at a cutting speed, thereby sumping the cutter bar within the coal, the clutch 108 thereafter being released. The operator then applies the friction clutch 76 and the cutter bar and supporting arm are swung laterally from right to left at a relatively slow cutting speed to a position adjacent the left hand rib, the clutch 76 thereafter being released. The friction clutch 107 is then applied and the apparatus is propelled bodily rearward along the trackway at a slow cutting speed, thereby effecting withdrawal of the cutter bar from beneath the coal. It is obvious that upon suitable control of the clutch device 47 the supporting arm 23 and the cutter bar 24 may be adjusted into a plurality of horizontal planes either at the level of the mine bottom or at a substantial distance above the mine bottom and any desired intermediate plane. If it is desired to change the angular position of the cutter bar relative to the horizontal, this may be accomplished simply by operating the ratchet and pawl mechanism 100 thereby rotating the nut 99 to effect axial adjustment of the screw 96 and as a result the shaft 90 is rotated, swinging the arms 91 and moving the rollers 92 within the guideways 93. As a result of this invention it will be noted that an improved coal mining apparatus is provided having improved kerf cutting mechanism including an improved offset pivotal mounting for the cutter bar whereby the latter may be positioned to cut at the level of the mine bottom outside the mine trackway. It will further be noted that an improved coal mining apparatus of the wheel mounted, bottom cutting type is provided having improved mechanism for adjusting the cutter bar vertically into different parallel horizontal planes and to adjust said cutter bar to a position at or near the level of the mine bottom, thereby enabling the cutting mechanism to extend the mine bottom. It will further be noted that by the improved arrangement provided herein the cutter bar may be easily and quickly positioned with its pivot outside the mine trackway and thereafter adjusted to a position at or near the level of the mine bottom, the improved adjusting and positioning mechanism being of a relatively simple and rugged construction and readily adapted to use with

a mining machine of standard design. These and other uses and advantages of the improved mining apparatus will be clearly apparent to those skilled in this art.

5. While there is in this application specifically described one form which the invention may assume in practice, it will be understood that this form of the same is shown for purposes of illustration and that the invention 10 may be modified and embodied in various other forms without departing from its spirit or the scope of the appended claims.

What I claim as new and desire to secure by Letters Patent is:

15. 1. In a mining apparatus, a portable frame, a motor on said frame, and cutting mechanism carried by said frame and driven by said motor including a pivoted supporting arm mounted on said frame for vertical 20 adjustment relative thereto into different parallel horizontal planes and swingable horizontally relative to said frame and motor, a cutter bar pivotally mounted on the outer end of said arm for independent swinging 25 movement relative thereto, means for holding said cutter bar in its different angular positions relative to said arm, and mechanism driven by said motor for swinging said arm about its pivot.

30. 2. In a mining apparatus, a wheeled truck, a frame mounted thereon for adjustment relative thereto, mechanism for adjusting said frame relative to said truck, and cutting mechanism carried by said adjustable frame 35 including a vertically adjustable support, mechanism for adjusting said support relative to said frame, an arm pivotally mounted on said support for swinging movement relative thereto about a vertical axis, a cutter 40 bar pivotally mounted on the outer end of said arm for independent swinging movement relative thereto about a parallel axis, means for holding said cutter bar in its different angular positions relative to said arm, 45 and mechanism for swinging said arm about its pivot.

3. In a mining apparatus, a wheeled truck, a frame mounted thereon for tilting movement relative thereto about a transverse axis, 50 mechanism for effecting tilting movement of said frame relative to said truck, and cutting mechanism carried by said tiltable frame including a vertically adjustable support, mechanism for adjusting said support relative to said frame, an arm pivotally mounted on said support for swinging movement relative thereto about a vertical axis, a cutter 55 bar pivotally mounted on the outer end of said arm for independent swinging movement relative thereto about a parallel axis, means for holding said cutter bar in its different angular positions relative to said arm, 60 and mechanism for swinging said arm about its pivot.

65. 4. In a mining apparatus, a wheeled sup-

port having its forward end overhanging the front support wheels, an arm pivotally mounted on the forward overhanging end of said support for swinging movement relative thereto about a vertical axis and adjustable rectilinearly into different parallel positions, said vertical axis lying to the front of the axes of the front support wheels, a cutter bar pivotally mounted on the outer end of said arm for independent swinging movement relative thereto about a parallel axis, means for holding said cutter bar in its different angular positions relative to said arm, mechanism for swinging said arm about its pivot, and mechanism for adjusting said arm into aforesaid positions to change the plane of cut of said cutter bar.

5. In a mining apparatus, a wheeled support having its forward end overhanging the front support wheels, an arm pivotally mounted on the forward overhanging end of said support for swinging movement relative thereto about a vertical axis in front of the axes of the front support wheels, a cutter bar pivotally mounted on the outer end of said arm for independent swinging movement relative thereto about a parallel axis, means for holding said cutter bar in its different angular positions relative to said arm, mechanism for swinging said arm about its pivot, and mechanism for adjusting said arm vertically relative to said support.

6. In a mining apparatus, a wheeled support having vertical guideways at the forward end thereof, a frame mounted for adjustment vertically along said guideways, mechanism for effecting vertical adjustment of said frame, an arm pivotally mounted on said frame for swinging movement relative thereto about a vertical axis in advance of said guideways, mechanism for swinging said arm relative to said frame, a cutter bar pivotally mounted at the outer end of said arm for independent swinging movement relative thereto about a parallel axis, and means for holding said cutter bar in its different angular positions relative to said arm.

7. In a mining apparatus, a wheeled truck, a support adjustably mounted on said truck, mechanism for effecting adjustment of said support relative to said truck, said support having vertical guideways at the forward end thereof, a frame mounted for adjustment vertically along said guideways, mechanism for effecting vertical adjustment of said frame, an arm pivotally mounted on said frame for swinging movement relative thereto about a vertical axis, mechanism for swinging said arm relative to said frame, a cutter bar pivotally mounted at the outer end of said arm for independent swinging movement relative thereto about a parallel axis, and means for holding said cutter bar

in its different angular positions relative to said arm.

8. In a mining apparatus, a wheeled truck, a support pivotally mounted thereon for tilting movement relative thereto about a transverse axis, mechanism for effecting tilting movement of said support relative to said truck, said support having vertical guideways at the forward end thereof, a frame mounted for adjustment vertically along said guideways, mechanism for effecting vertical adjustment of said frame, an arm pivotally mounted on said frame for swinging movement relative thereto about a vertical axis, mechanism for swinging said arm relative to said frame, a cutter bar pivotally mounted at the outer end of said arm for independent swinging movement relative thereto about a parallel axis, and means for holding said cutter bar in its different angular positions relative to said arm.

9. In a mining apparatus, a wheeled support having vertical guideways at the forward end thereof, a frame mounted for adjustment vertically along said guideways, mechanism for effecting vertical adjustment of said frame, an arm pivotally mounted on said frame for swinging movement relative thereto about a vertical axis in advance of said guideways, mechanism for swinging said arm relative to said frame, a cutter bar pivotally mounted at the outer end of said arm for independent swinging movement relative thereto about a parallel axis, and means comprising a releasable locking device for holding said cutter bar in its different angular positions relative to said arm.

10. In a mining apparatus, a wheeled support having front and rear truck wheels, an elongated arm pivotally mounted at the forward end of said support in advance of the front truck wheels for swinging movement about a vertical axis, mechanism for swinging said arm relative to said support, a cutter bar pivotally mounted on the outer extremity of said arm for free swinging movement relative thereto about a parallel axis, and means for holding said cutter bar in different predetermined angular positions relative to said arm.

11. In a mining apparatus a wheeled truck, a frame adjustably mounted thereon, cutting mechanism carried by said adjustable frame at the forward end thereof including a vertical guideway, a support adjustable vertically along said guideway, a frame pivotally mounted on said support for swinging movement relative thereto about a vertical axis, a cutter bar pivotally mounted at the outer extremity of said pivoted frame for swinging movement relative thereto about a parallel axis, and means for holding said cutter bar in its different angular positions relative to said pivoted frame.

12. In a mining apparatus, a wheeled

truck, a machine frame pivotally mounted thereon for tilting movement about a transverse axis, cutting mechanism carried at the forward end of said tiltable frame including a rigid cutter head frame, a third frame adjustable vertically relative to said cutter head frame, an elongated arm pivotally mounted at its rear end on said third frame for swinging movement relative thereto about a vertical axis, a cutter bar pivotally mounted at the outer end of said arm for independent swinging movement relative thereto about a parallel axis, and means for holding said cutter bar in its different angular positions relative to said arm.

13. In a mining apparatus, a wheeled truck, a frame thereon having a vertical guideway disposed in advance of said truck, a support mounted for vertical adjustment along said guideway, an arm pivotally mounted at its rear end on said support for swinging movement relative thereto about a vertical axis in advance of said guideway, a cutter bar pivotally mounted at the outer end of said arm for independent swinging movement relative thereto about a parallel axis, and means for locking said cutter bar in its different angular positions relative to said arm.

14. In a mining apparatus, a wheeled truck, a machine frame adjustably mounted thereon, mechanism for effecting adjustment of said frame relative to said truck, said frame having a vertical guideway disposed in advance of said truck, a support adjustable vertically relative to said guideway, an arm pivotally mounted at its rear end on said support for swinging movement relative thereto about a vertical axis, a cutter bar pivotally mounted at the outer end of said arm for independent swinging movement relative thereto about a parallel axis, and means for locking said cutter bar in its different angular positions relative to said arm.

15. In a mining apparatus, a wheeled truck, a machine frame pivotally mounted thereon to rock about a transverse axis, mechanism for effecting tilting movement of said frame relative to said truck, said frame having a vertical guideway disposed in advance of said truck, a support adjustable vertically along said guideway, mechanism for adjusting said support relative to said frame, an elongated arm pivotally mounted at its rear end on said support for swinging movement relative thereto about a vertical axis, a cutter bar pivotally mounted at the outer end of said arm, and means for locking said cutter bar in its different angular positions relative to said arm.

16. In a mining apparatus, a wheeled truck, cutting mechanism thereon including a cutter head, a vertical guideway on said head, a support adjustable vertically along said guideway, mechanism for adjusting said

support, an arm pivotally mounted on said support for swinging movement relative thereto about a vertical axis in advance of the axes of the front truck wheels, a cutter bar pivotally mounted at the outer end of said arm for independent swinging movement relative thereto, and means for locking said cutter bar in its different angular positions relative to said arm.

17. In a mining apparatus, a wheeled truck, cutting mechanism thereon including a cutter head, a vertical guideway on said head, a support adjustable vertically along said guideway, mechanism for adjusting said support, an arm pivotally mounted on said support for swinging movement relative thereto about a vertical axis in advance of the axes of the front truck wheels, a cutter bar pivotally mounted at the outer end of said arm for independent swinging movement relative thereto, means for locking said cutter bar in its different angular positions relative to said arm, and mechanism for effecting swinging movement of said arm at a fast positioning speed in one direction and at a slow cutting speed in the opposite direction.

18. In a mining apparatus, a wheel-supported frame and cutting mechanism carried thereby including a pivoted supporting arm mounted on said frame for horizontal swinging movement about a vertical axis in advance of all of the frame supporting wheels for vertical adjustment relative to said frame into different parallel horizontal planes, a cutter bar pivotally mounted on the outer end of said arm for independent swinging movement relative thereto, means for holding said cutter bar in its different angular positions relative to said arm, mechanism for swinging said arm about its pivot, and mechanism for propelling the apparatus along a mine trackway at a relatively high transport speed or a relatively low cutting speed.

19. In a mining apparatus, a wheeled truck, cutting mechanism thereon including a cutter head, a vertical guideway on said head, a support adjustable vertically along said guideway, mechanism for adjusting said support, an arm pivotally mounted on said support for swinging movement relative thereto about a vertical axis in advance of the axes of the front truck wheels, a cutter bar pivotally mounted at the outer end of said arm for independent swinging movement relative thereto, means for locking said cutter bar in its different angular positions relative to said arm, and mechanism for propelling the apparatus along a mine trackway at a relatively high transport speed or a relatively low cutting speed.

20. In a mining apparatus, a wheeled support adapted to run along a mine trackway, a frame mounted on the forward end of said support for horizontal swinging movement relative thereto about a vertical axis, kerf

cutting mechanism including a cutter bar pivotally mounted at the outer extremity of said frame for independent swinging movement relative thereto, means for holding said cutter bar in its different angular positions relative to said frame, mechanism for rectilinearly adjusting said frame into different positions relative to the trackway to change the plane of operation of said cutter bar, a motor carried by said support, and devices driven by said motor for actuating said cutting mechanism, for swinging said frame about its axis relative to said support, for adjusting said frame to change the plane of operation of said cutter bar and for driving the support wheels to propel the apparatus along the mine trackway.

21. In a mining apparatus, a wheeled support adapted to run along a mine trackway, a frame mounted on the forward end of said support for horizontal swinging movement relative thereto about a vertical axis and adjustable vertically into different elevated positions relative to the trackway, kerf cutting mechanism including a cutter bar pivotally mounted on said frame for swinging movement relative thereto about an axis parallel to said frame axis, means for holding said cutter bar in its different angular positions relative to said frame, a motor carried by said support, and devices driven by said motor for actuating said cutting mechanism, for swinging said frame about its axis, for adjusting said frame vertically into different elevated positions relative to the trackway, and for driving the support wheels to propel the apparatus along the mine trackway.

22. In a mining apparatus, a wheeled support adapted to run along a mine trackway, and having its forward end overhanging the front support wheels, an arm mounted on the forward overhanging end of said support for swinging movement relative thereto about a vertical axis and adjustable into different elevated positions, said vertical axis lying to the front of the axes of the front support wheels, kerf cutting mechanism including a cutter bar pivotally mounted on the outer extremity of said arm for independent swinging movement relative thereto about a parallel axis, means for holding said cutter bar in its different angular positions relative to said arm, means for swinging said arm about its pivot, and means for adjusting said arm into aforesaid elevated positions.

23. In a mining apparatus, a wheeled support adapted to run along a mine trackway, and having its forward end overhanging the front support wheels, a horizontal frame mounted on the forward overhanging end of said support for swinging movement relative thereto about a vertical axis in advance of the axes of the front support wheels, said frame being adjustable into different elevated positions relative to the trackway, kerf cutting

mechanism including a cutter bar pivotally mounted on the outer extremity of said horizontal frame for independent swinging movement relative thereto about a parallel axis, means for holding said cutter bar in its different angular positions relative to said frame, means for swinging said frame horizontally about its axis to position said cutter bar outside the mine trackway, and mechanism for adjusting said frame into aforesaid elevated positions.

24. In a mining apparatus, a wheeled support adapted to run along a mine trackway, a frame mounted thereon to rock about a transverse axis, an arm pivotally mounted on the forward end of said frame and swingable horizontally relative thereto, a cutter bar pivotally mounted on the outer extremity of said arm for independent swinging movement relative thereto about a parallel axis, means for holding said cutter bar in its different angular positions relative to said arm, and means for swinging said arm about its pivot relative to said frame.

25. In a mining apparatus, a wheeled support adapted to run along a mine trackway, a frame mounted thereon to rock about a transverse axis to vary its angular position relative to the horizontal, an arm pivotally mounted on the forward end of said tiltable frame for horizontal swinging movement relative thereto, a cutter bar pivotally mounted on the outer extremity of said arm for independent swinging movement relative thereto, means for holding said cutter bar in its different angular positions relative to said arm, and mechanism for swinging said arm about its pivot relative to said frame.

26. In a mining apparatus, a wheeled truck adapted to run along the mine trackway, a support thereon, said support having a guideway at the forward end thereof, a frame mounted for adjustment rectilinearly along said guideway, mechanism for effecting adjustment of said frame, an arm pivotally mounted on said frame for swinging movement relative thereto about a vertical axis in advance of said guideway, mechanism for swinging said arm relative to said frame, a cutter bar pivotally mounted at the outer extremity of said arm for independent swinging movement relative thereto about a parallel axis, and means for holding said cutter bar in its different angular positions relative to said arm.

27. In a mining apparatus, a wheeled support adapted to run along a mine trackway, a frame mounted thereon for adjustment vertically relative to the trackway, mechanism for effecting vertical adjustment of said frame, an arm pivotally mounted on said frame for swinging movement relative thereto about a vertical axis in advance of the axes of the front support wheels, mechanism for swinging said arm relative to said

frame, a cutter bar pivotally mounted on the outer extremity of said arm for independent swinging movement relative thereto about a parallel axis, and means comprising a releasable locking device for holding said cutter bar in its different angular positions relative to said arm or to permit free swinging movement of said cutter bar relative to said arm.

28. In a mining apparatus, a wheeled truck adapted to run along a mine trackway, cutting mechanism carried by said truck including a rigid cutter head frame, a frame adjustable vertically relative to said cutter head frame, an elongated arm pivotally mounted at its rear end on said adjustable frame for swinging movement relative thereto about a vertical axis in advance of the axes of the forward truck wheels, a cutter bar pivotally mounted at the outer extremity of said arm for independent swinging movement relative thereto about a parallel axis, and means for holding said cutter bar in its different angular positions relative to said arm.

29. In a mining apparatus, a wheeled support adapted to run along a mine trackway, kerf cutting mechanism on said support including a cutter head, a frame adjustably mounted on said cutter head for movement into a plurality of parallel planes, an arm pivotally mounted on said frame for swinging movement relative thereto about an upright axis in advance of the axes of the forward support wheels, a cutter bar pivotally mounted at the outer extremity of said arm, means for holding said cutter bar in its different angular positions relative to said arm, mechanism for swinging said arm about its pivot, and mechanism for adjusting said frame relative to said cutter head.

30. In a mining apparatus a wheeled truck adapted to run along a mine trackway, a support on said truck having a portion overhanging the front end of said truck and adjustable into different positions relative to the horizontal, a frame mounted on said overhanging support portion for swinging movement relative thereto about a vertical axis and having a portion adapted to project laterally outside the mine trackway, kerf cutting mechanism including a cutter bar pivotally mounted at the outer extremity of said projecting frame portion for swinging movement relative thereto about a parallel axis, a motor carried by said truck, and devices driven by said motor for actuating said cutting mechanism for swinging said frame about its pivot and for driving the support wheels to propel the apparatus along the mine trackway.

31. In a mining apparatus, a wheeled truck adapted to run along a mine trackway, a motor mounted on said truck for driving the truck wheels to propel the apparatus, a frame rotatably mounted on said truck for move-

- ment relative thereto about a vertical axis and having a projecting portion adapted to project outwardly beyond the side of the trackway, devices driven by said motor for 5 rotating said frame about its axis, kerf cutting mechanism including a cutter bar pivotally mounted on the outer extremity of said frame and disposable in a position to cut a horizontal kerf at the level of the mine bottom outside and below the level of the mine trackway, means for holding said cutter bar in its different angular positions relative to said rotatable frame, devices driven by said motor for actuating said cutting mechanism 10 and for rotating said frame relative to said truck, and mechanism for adjusting said frame vertically relative to the truck wheels to vary the plane of operation of said cutter bar.
- 15 32. In a mining apparatus, a wheeled truck adapted to run along a mine trackway, a motor on said truck, devices driven by said motor for driving the truck wheels to propel the apparatus, a frame mounted on said truck 20 for rotation relative thereto about a vertical axis and adjustable rectilinearly into different positions relative to said truck, said frame having a projecting portion extending outwardly beyond the side of the mine trackway, kerf cutting mechanism including a cutter bar pivotally mounted on the outer extremity of said frame, means for holding said cutter bar in its different angular positions relative to said frame, devices driven by said 25 motor for rotating said frame relative to said truck to position said cutter bar to cut a kerf at the level of the mine bottom outside and below the level of the mine trackway, devices for adjusting said frame relative to 30 said truck, and devices driven by said motor for actuating the cutting mechanism and for rotating said frame relative to said truck.
33. In a mining apparatus, a wheeled truck adapted to run along a mine trackway, a 35 frame mounted on said truck at the forward end thereof to swing horizontally relative thereto about a vertical axis in advance of the axes of the forward truck wheels, said frame being swingable to a position wherein it projects beyond the side of the mine trackway, a cutter bar pivotally mounted at the outer extremity of said frame for swinging movement relative thereto about a parallel axis, and mechanism for adjusting said frame relative to said truck to position said cutter bar to cut a horizontal kerf at the level of the mine bottom outside and below the level of the mine trackway, said adjusting mechanism including cooperating screw and nut elements one of which is rotatable by power, 40 and means for holding the other element against rotation to effect such adjustment.
34. In a mining apparatus, a wheeled truck adapted to run along a mine trackway, a frame mounted on said truck at the forward end thereof to swing horizontally relative thereto about a vertical axis in advance of the axes of the forward truck wheels, said frame being swingable to a position wherein it projects beyond the side of the mine trackway, a cutter bar pivotally mounted at the outer extremity of said frame for swinging movement relative thereto about a parallel axis, and mechanism for adjusting said frame relative to said truck to position said cutter bar to cut a horizontal kerf at the level of the mine bottom outside and below the level of the mine trackway, said adjusting mechanism including cooperating screw and nut elements one of which is rotatable by power, 45 and swingable to a position wherein it projects beyond the side of the mine trackway, a cutter bar pivotally mounted at the outer extremity of said frame for swinging movement relative thereto about a parallel axis, and mechanism for adjusting said frame relative to said truck to position said cutter bar to cut a horizontal kerf at the level of the mine bottom outside and below the level of the mine trackway, said adjusting mechanism including cooperating screw and nut elements one of which is rotatable by power, 50 and means for holding the other element against rotation to effect such adjustment.
35. In a mining apparatus, a wheeled truck adapted to run along a mine trackway, kerf cutting mechanism thereon including a frame pivotally mounted at the forward end of said truck for horizontal swinging movement relative thereto about a vertical axis and adjustable vertically into different elevated positions relative to the trackway, said frame when in one position overlying and projecting outwardly beyond the side of the trackway, a cutter bar pivotally mounted at the outer extremity of said frame for swinging movement relative thereto about a parallel axis, mechanism for adjusting said frame in aforesaid elevated positions, and mechanism for swinging said frame relative to said truck including a frictionally controlled frame swinging mechanism having reversing gearing operable to effect frame swing in either of opposite directions.
36. In a mining apparatus, a wheeled truck adapted to run along a mine trackway, kerf cutting mechanism thereon including a frame pivotally mounted at the forward end of said truck for horizontal swinging movement relative thereto about a vertical axis and adjustable vertically into different elevated positions relative to the trackway, said frame when in one position overlying and projecting outwardly beyond the side of the trackway, a cutter bar pivotally mounted at the outer extremity of said frame for swinging movement relative thereto about a parallel axis, mechanism for adjusting said frame in aforesaid elevated positions, and mechanism for swinging said frame relative to said truck including a frictionally controlled frame swinging mechanism having reversing gearing operable to effect frame swing in either of opposite directions.
37. In a mining apparatus, a wheeled truck adapted to run along a mine trackway, kerf cutting mechanism thereon including a frame pivotally mounted at the forward end of said truck for horizontal swinging movement relative thereto about a vertical axis and adjustable vertically into different elevated positions relative to the trackway, said frame when in one position overlying and projecting outwardly beyond the side of the trackway, a cutter bar pivotally mounted at the outer extremity of said frame for swinging movement relative thereto about a parallel axis, mechanism for adjusting said frame in aforesaid elevated positions, and mechanism for swinging said frame relative to said truck including a frictionally controlled frame swinging mechanism having reversing gearing operable to effect frame swing in either of opposite directions.

way, a cutter bar pivotally mounted at the outer extremity of said frame for swinging movement relative thereto about a parallel axis, mechanism for adjusting said frame in aforesaid elevated positions, and mechanism for swinging said frame relative to said truck including reverse frictions selectively operable to effect swinging of said frame in either of opposite directions.

38. In a mining apparatus, a wheeled truck adapted to run along a mine trackway, kerf cutting mechanism thereon including a frame pivotally mounted at the forward end of said truck for horizontal swinging movement relative thereto about a vertical axis located a substantial distance in advance of the front truck wheels and adjustable into different elevated positions relative to the trackway, said frame when in one position overlying and projecting outwardly beyond the side of the trackway, a cutter bar pivotally mounted at the outer extremity of said frame for swinging movement relative thereto about a parallel axis, mechanism for adjusting said frame in aforesaid elevated positions, and motor operated devices for swinging said frame relative to said truck and including reversing mechanism operative to effect swinging of said frame in either of opposite directions.

39. In a mining apparatus, a wheeled support adapted to run along a mine trackway, a hollow arm mounted on said support at the forward end thereof to swing horizontally relative thereto about a vertical axis and for adjustment in a vertical direction relative to the trackway, said arm being swingable to a position wherein it projects beyond the side of the mine trackway, kerf cutting mechanism including a cutter bar pivotally mounted at the outer extremity of said arm for swinging movement relative thereto about a parallel axis, mechanism for adjusting said arm in aforesaid vertical direction, mechanism for swinging said arm relative to said support, and devices for actuating said cutting mechanism including rotatable transmission elements coaxial with the pivotal axis of said cutter bar and said arm axis respectively, and transmission means housed in said arm and connecting said rotatable transmission elements in driving relation.

40. In a mining apparatus, a wheeled support adapted to run along a mine trackway, a hollow arm mounted on said support at the forward end thereof to swing horizontally relative thereto about a vertical axis, said arm being swingable to a position wherein it projects beyond the side of the mine trackway, kerf cutting mechanism including a cutter bar pivotally mounted at the outer extremity of said arm for swinging movement relative thereto about a parallel axis, mechanism for swinging said arm relative to said support, and devices for actuating said cut-

ting mechanism including sprockets coaxial with the pivotal axis of said cutter bar and said arm axis respectively, and a transmission chain housed in said arm and connecting said sprockets in driving relation.

41. In a mining apparatus, a wheeled support adapted to run along a mine trackway, an arm mounted on said support at the forward end thereof in advance of the front support wheels to swing horizontally relative to said support about a vertical axis and for adjustment in a vertical direction relative to the trackway, said vertical axis lying to the front of the axes of the front support wheels, said arm being swingable to a position wherein it projects beyond the side of the mine trackway, mechanism for swinging said arm relative to said support, mechanism for adjusting said arm in aforesaid vertical direction, a cutter bar, and a pivotal mounting for said cutter bar at the outer extremity of said arm including an annular guideway and a cooperating cylindrical guide on said arm and cutter bar respectively.

42. In a mining apparatus, a wheeled support adapted to run along a mine trackway, an arm mounted on said support at the forward end thereof to swing horizontally relative thereto about a vertical axis located a substantial distance in advance of the front support wheels, said arm being swingable to a position wherein it projects beyond the side of the mine trackway, mechanism for swinging said arm relative to said support, a cutter bar, and a pivotal mounting for said cutter bar at the outer extremity of said arm including a depending cylindrical bearing support on said arm, a cooperating annular bearing member carried by said bar, and supplemental bearing means for said cutter bar arranged concentrically with aforesaid bearing means.

43. In a mining apparatus, a wheeled support adapted to run along a mine trackway, an arm mounted on said support at the forward end thereof to swing horizontally relative thereto about a vertical axis located a substantial distance in advance of the front support wheels, said arm being swingable to a position wherein it projects beyond the side of the mine trackway, mechanism for swinging said arm relative to said support, a cutter bar, and a pivotal mounting for said cutter bar at the outer extremity of said arm including a depending cylindrical bearing support on said arm, a cooperating annular bearing member carried by said bar, and supplemental bearing means arranged concentrically with aforesaid bearing means including an annular guideway and a cooperating an-

125
44. In a mining apparatus, a wheeled support adapted to run along a mine trackway, an arm mounted on said support at the forward end thereof to swing horizontally rela-

tive thereto about a vertical axis in advance of the axes of the front support wheels, said arm being swingable to a position wherein it projects beyond the side of the mine trackway, and mechanism for swinging said arm relative to said support, a cutter bar pivotally mounted on the outer extremity of said arm for free swinging movement relative thereto, and means for locking said cutter bar to said arm for swinging movement therewith including cooperating locking elements carried by said arm and cutter bar respectively.

45. In a mining apparatus, a wheeled support adapted to run along a mine trackway, an arm mounted on said support at the forward end thereof to swing horizontally relative thereto about a vertical axis in advance of the axes of the front support wheels, said arm being swingable to a position wherein it projects beyond the side of the mine trackway, and mechanism for swinging said arm relative to said support, a cutter bar pivotally mounted on the outer extremity of said arm for free swinging movement relative thereto, and means for locking said cutter bar to said arm for swinging movement therewith including a locking pin carried by said arm and cooperating locking recesses on said cutter bar.

46. In a mining apparatus, a wheeled support adapted to run along a mine trackway, an arm mounted on said support at the forward end thereof to swing horizontally relative thereto about a vertical axis and for adjustment in a vertical direction relative to the trackway, said vertical axis lying to the front of the axes of the front support wheels, said arm being swingable to a position wherein it projects beyond the side of the mine trackway, a cutter bar pivotally mounted at the outer extremity of said arm for swinging movement relative thereto about a parallel axis, mechanism for adjusting said arm in aforesaid vertical direction, and mechanism for swinging said arm relative to said support including a gear carried by said arm, a gear meshing with said gear, and motor operated devices carried by said support and including a motor relative to which said arm is swingable for rotating said last mentioned gear to swing said arm about its pivot.

47. In a mining apparatus, a wheeled support adapted to run along a mine trackway, a second support mounted on the forward end of said first support for rectilinear adjustment vertically relative thereto, motor operated devices for adjusting said second support relative to said first support, an arm mounted on said second support to swing horizontally relative thereto about a vertical axis in front of the axes of the front support wheels, said arm being swingable to a position wherein it projects beyond the side of the mine trackway, a cutter bar pivotally

mounted at the outer extremity of said arm for swinging movement relative thereto about a parallel axis, and motor operated devices for swinging said arm relative to said second support.

48. In a mining apparatus, a wheeled support adapted to run along a mine trackway, a second support mounted on said first support for adjustment relative thereto, a third support mounted on said second support at the forward end thereof for rectilinear adjustment relative to said second support, motor operated devices for adjusting said third support relative to said second support, an arm mounted on said third support to swing horizontally relative thereto about a vertical axis, said arm being swingable to a position wherein it projects beyond the side of the mine trackway, a cutter bar pivotally mounted at the outer extremity of said arm for swinging movement relative thereto about a parallel axis, and motor operated devices for swinging said arm relative to said third support.

49. In a mining apparatus, a wheeled truck adapted to travel along a mine trackway, a support on said truck overhanging the front end of said truck, a horizontally swingable arm pivotally mounted on said overhanging support for horizontal swinging relative thereto about a vertical axis in advance of the front truck wheels, a kerf cutter pivotally mounted on the outer extremity of said arm for free swinging movement relative thereto, and releasable means for locking said kerf cutter in different predetermined positions relative to said arm.

50. In a mining apparatus, a wheeled truck adapted to travel along a mine trackway, a support on said truck overhanging the front end of said truck, a horizontally swingable arm pivotally mounted on said overhanging support, a kerf cutter pivotally mounted on the outer extremity of said arm for free swinging movement relative thereto, releasable means for locking said kerf cutter in different predetermined positions relative to said arm, and mechanism for adjusting said arm and kerf cutter in a vertical direction to position said kerf cutter to cut a kerf at the level of the mine bottom outside and below the level of the mine trackway.

51. In a mining apparatus, a wheeled truck adapted to travel along a mine trackway, a support thereon adjustable in a vertical direction relative to the trackway and overhanging the front end of said truck, an arm pivotally mounted on the overhanging portion of said support for horizontal swinging movement relative thereto about a vertical axis in advance of the axes of the forward truck wheels, and a kerf cutter pivotally mounted on the outer extremity of said arm for horizontal swinging movement relative thereto, said arm being swingable lat-

erally to position said kerf cutter with its pivot outside the trackway.

52. In a mining apparatus, a wheeled truck adapted to travel along a mine trackway, a support thereon adjustable in a vertical direction relative to the trackway and overhanging the front end of said truck, an arm pivotally mounted on the overhanging portion of said support for horizontal swinging movement relative thereto about a vertical axis in advance of the axes of the forward truck wheels, a kerf cutter pivotally mounted on the outer extremity of said arm for horizontal swinging movement relative thereto, said arm being swingable laterally to position said kerf cutter with its pivot outside the trackway, and means for adjusting said support in aforesaid vertical direction to position said kerf cutter to cut a kerf 20 at the level of the mine bottom outside and below the level of the mine trackway.

In testimony whereof I affix my signature.
CHARLES F. OSGOOD.
